MARTIN L. KEYES, OF FAIRFIELD, MAINE, ASSIGNOR TO KEYES FIBRE COMPANY, OF SHAW-MUT, MAINE, A CORPORATION OF MAINE.

JOINT FOR MACHINES FOR MOLDING ARTICLES FROM PULP.

No. 903,870.

Specification of Letters Patent.

Patented Nov. 17, 1908.

Application filed July 22, 1908. Serial No. 444,691.

To all whom it may concern:

Be it known that I, MARTIN L. KEYES, a citizen of the United States, and a resident of Fairfield, in the county of Somerset and State of Maine, have invented an Improvement in Joints for Machines for Molding Articles from Pulp, of which the following description, in connection with the accompanying drawing, is a specification, like letters on the drawing representing like parts.

This invention relates to the joint construction of the pivot member of the mold in a machine for molding articles from pulp, such for example as shown and described in my prior patents No. 759,616, granted May 10, 1904, and No. 788,138, granted April 25, 1905.

In a machine of this character a traveling mold is employed, the said mold being made of two parts, one of which is pivoted with respect to the other. The mold parts are hollow or chambered and connections are made to the said chambers through the arms supporting the mold parts, to enable the air in said chambers to be exhausted or compressed as required in the operations of forming the pulp articles. At one period in their travel the mold parts are pressed together by a powerful compressing device in order to compact the pulp into the desired shape and reduce the amount of water therein. A machine of this type must of necessity be of a strong construction to stand the speed at which it is run, the wear and tear of the moving parts, and the powerful compression to which the mold parts are subjected. One at least of the mold parts in its travel passes through a vat of liquid pulp, and the pulp, together with other foreign matters, is splashed more or less over the entire machine, and particularly over the mold carrying arms, and consequently over the pivotal joint connecting the two arms.

It is necessary that the pivot arm carrying the one mold part shall swing back and forth on its pivot with great accuracy in order that the two parts of the mold may come into exact juxtaposition in order to form the molded article properly. It is also necessary that this joint shall be kept well lubricated under these trying conditions. These and other considerations which will be apparent from an examination of the character of the machine in question and its workings render the joint portion between

the pivot and the fixed mold carrying arms a vital feature in the machine. My invention relates to this feature and I have devised a form of joint which possesses great strength, secures the accurate registry of the mold parts, provides for a thorough and continuous lubrication of the joint, renders impossible the entrance of any foreign matters to the surfaces of the joint, and enables the parts to be readily taken apart and repaired or replaced when desired.

The invention will more fully appear from the accompanying description and drawings and will be particularly pointed out in the appended claims.

The drawings represent only the joint portion in question and one end of the mold carrying arms, the general construction and arrangement of the machine as a whole being fully set forth in the above-mentioned patents.

In the drawings, Figure 1 is a front elevation of the upper end of the mold carrying arms looking toward the back of the pivot arm. Fig. 2 is a plan view of the lower portion of the device shown in Fig. 1. Fig. 3 is an enlarged elevation, partly in central cross-section, of the lower portion of the parts shown in Fig. 1. Fig. 4 is a side elevation of the parts shown in Figs. 2 and 3.

It is unnecessary here to describe for the purposes of this invention the machine and its operation which are fully set forth in the above-mentioned patents.

The parts of the present invention in the form herein illustrated include the U-shaped member A, adapted to extend around the hollow arm leading to the fixed mold member and to be bolted by means of bolts passing through the holes a to the stiffening ring of the machine, as illustrated for example in the said Patent No. 759,616.

The U-shaped member A carries preferably integral therewith as herein illustrated, the upper end B of the hollow arm containing the air passageway for the pivoted mold member and the bracket C. The upper end of the hollow arm B is herein shown as separated from the main portion of the arm and adapted to be united thereto by the screw-threaded portion b. The air passageway b² is closed at its upper end by the bracket C which is herein shown as formed integral with the upper end B of the hollow arm. A passageway b extends from the

outer face of the bracket C into and communicates with the passageway b^3 coming up through the hollow arm.

The bracket C carries at its upper end and 5 has mounted therein a stub-shaft D, having a long projecting bearing portion extending laterally from the bracket. The stub-shaft is held in place in the bracket C by a shoulder d^1 , and a nut d^2 threaded on to the end 10 of the shaft between which shoulder and nut the bracket is clamped. A small set-screw d^3 may also be employed and passes through the bracket and engages with the shaft.

15 The elongated bearing portion of the shaft D is provided with a plurality of longitudinal grooves d^4 and with an annular groove d^5 intersecting the longitudinal grooves. These screws serve to secure the 20 lubrication of the shaft as will be explained. The stub-shaft D is also provided at its projecting end with a reduced portion carrying a washer d^6 , and locking nuts d^7 , d^8 , threaded thereon.

25 The lower end of the hollow arm to which is connected and which supports the hollow pivoted mold member F, is shown at E. The air passageway e in this hollow arm E is closed at its lower end, but has communicating therewith an air passageway e^2 , extending in laterally from the exterior of the arm.

The lower end of the arm E is formed as a long transverse bearing E^2 adapted to extend and fit over the projecting portion of the shaft D.

30 The bearing E^2 is provided with a hole and a plug e^3 therein in alinement with the annular groove d^5 . The outer end of the 40 bearing E^2 is screw-threaded and a cap G is fitted thereon to inclose the end of the bearing and contain therein the washer d^6 , and the nuts d^7 , d^8 . A gasket H of suitable material, such as brass, when the bracket and 45 bearing are formed of iron, is interposed between the said bracket and the said bearing.

A flexible tube, preferably of rubber material, shown at K, connects the air passageways b^3 and e^2 , and extends around the pivotal joint, securing a continuous air passage 50 from the hollow arm B to the hollow arm E.

The operation of the device will be apparent. When the parts have been placed in position as illustrated, the nuts d^7 and d^8 55 are tightened up until there is a close fit between the end of the bearing E^2 , the gasket H and the bracket C. The cap G incloses the end of the bearing, and thus it is impossible for any water, pulp, grit or other foreign matter to find its way into the joint 60 between the surfaces of the shaft D and the bearing E^2 . These surfaces are kept in constant and perfect lubrication by means of hard grease placed in the opening of the 65 bearing E^2 and forced in by means of the

grease cup e^3 , so that it enters the annular groove d^5 and is distributed by the longitudinal grooves d^4 throughout the entire bearing surface.

The length of the projecting portion of 70 the shaft D and of the bearing E^2 is such that accurate movement of the pivoted arm and the consequent accurate registry of the mold members is assured.

The air passageway for securing a vacuum 75 or a plenum in the chamber of the pivoted mold member does not at any point pass through the joint but is carried by means of the flexible tube K entirely around the joint. There is thus rendered unnecessary the 80 maintenance of any air-tight movable joint. The construction thus described has been found to work with great satisfaction and to secure the desired results under the trying 85 conditions to which such a device is subjected in a machine of the character in question.

Having described my invention, what I claim as new and desire to secure by Letters Patent, is:

90

1. In an apparatus of the class described, a hollow arm closed at one end, a bracket at the said end thereof, a stub-shaft mounted in and projecting from said bracket, a hollow mold carrying arm closed at its end and provided with an elongated bearing adapted to fit over the projecting portion of said shaft, locking means on the end of said shaft for holding said bearing snugly up against said bracket, a flexible tube connecting the 95 hollow of said arms, and extending around said bracket, shaft and bearing.

100

2. In an apparatus of the class described, a hollow arm closed at one end, a bracket at the said end thereof, a stub-shaft mounted in 105 and projecting from said bracket, a hollow mold carrying arm closed at its end and provided with an elongated bearing adapted to fit over the projecting portion of said shaft, locking means on the end of said shaft for holding said bearing snugly up against said bracket, a removable cap on the end of said bearing inclosing said locking means.

110

3. In an apparatus of the class described, a hollow arm closed at one end, a bracket at 115 the said end thereof, a stub-shaft mounted in and projecting from said bracket, a hollow mold carrying arm closed at its end and provided with an elongated bearing adapted to fit over the projecting portion of said shaft, a metal gasket between said bracket and said bearing, locking means on the end of said shaft for holding said bearing snugly up against said bracket, a removable cap on the end of said bearing inclosing said locking 120 means.

125

4. In an apparatus of the class described, a hollow arm closed at one end, a bracket at the said end thereof, a stub-shaft mounted in 130 and projecting from said bracket, longitudi-

130

nal grooves and an annular groove in the surface of said shaft, a hollow mold carrying arm closed at its end and provided with an elongated bearing adapted to fit over the 5 projecting portion of said shaft, a hole in said bearing in line with said annular groove, and a grease cup in said hole, locking means on the end of said shaft for holding said bearing snugly up against said bracket, a 10 flexible tube connecting the hollow of said arms, and extending around said bracket, shaft and bearing.

5. In an apparatus of the class described, a hollow arm closed at one end, a bracket at 15 the said end thereof, a stub-shaft mounted in and projecting from said bracket, longitudinal grooves and an annular groove in the sur-

face of said shaft, a hollow mold carrying arm closed at its end and provided with an elongated bearing adapted to fit over the projecting portion of said shaft, a hole in said bearing in line with said annular groove, and a grease cup in said hole, a flexible tube connecting the hollow of said arms, and extending around said bracket, shaft and 20 bearing.

In testimony whereof, I have signed my name to this specification, in the presence of two subscribing witnesses.

MARTIN L. KEYES.
